UNITED STATES PATENT OFFICE

JAMES S. TAYLOR, OF WYNONA, OKLAHOMA, ASSIGNOR OF ONE-HALF TO LORY J. MILDREN, OF PONCA CITY, OKLAHOMA

BECKET

Application filed June 17, 1927. Serial No. 199,578.

This invention relates to improvements in clevis constructions for use upon traveling blocks for the support of elevators and the like, as used in the oil industry.

5 The primary object of this invention is the provision of an improved clevis which may with facility receive either single or double link well casing elevators, doing away with the common casing hooks now in use, and 10 furnishing a much more efficient and safer device.

A further object of this invention is the provision of a resiliently mounted clevis or becket of novel construction.

15 A further object of this invention is the provision of an improved swivelly mounted becket for traveling blocks.

A further object of this invention is the provision of a novel becket of a sectional nature which may be opened to receive therein an elevator link in a novel relation.

Other objects and advantages of this invention will be apparent during the course of 25 the following detailed description.

In the accompanying drawings, forming a part of this specification, and wherein similar reference characters designate corresponding parts throughout the several views,

30 Figure 1 is a side elevation, partly in section showing the relation in which the improved becket or swivel is associated with a traveling block for the support of an elevator.

35 Figure 2 is a side elevation showing the position which the improved becket assumes in its swivel frame when not in use.

Figure 3 is an edge elevation viewed at right angles to the views in Figures 1 and 2, 40 showing the becket opened.

Figure 4 is a view of the improved becket and traveling block similar to Figure 1, but showing a double link elevator supported thereby.

45 Figures 5 and 6 are cross sectional views taken substantially on their respective lines in Figure 4 of the drawings.

Figure 7 is a modified form of becket showing how the becket may be used directly upon 50 a traveling block, without the intermediary

of its swivel frame for receiving a support, as shown in the preferred embodiment.

In the drawings, wherein for the purpose of illustration is shown preferred and modified forms of the invention, the letter A may generally designate a traveling block of any approved construction, upon which the improved becket B may be mounted, either directly, as illustrated in Figure 7, or thru the intermediary of a swivel frame C, for the support of either single link elevators D, as illustrated in Figure 1, or the support of double link elevators E as illustrated in Figure 4.

The traveling block A may include the spaced plates 15, as in well known construction, having a center pin 16 extending therethrough for supporting sheaves 17 in a rotatable relation, as well understood in the art. The particular traveling block shown in the drawings is a triple sheave traveling block. 70 The plates 15 may have suitable spacers 18 connected by cross bolts 19, and at the lower part of the traveling block a vertical supporting bolt 20 is provided, which may be utilized for supporting the swivel frame C, 75 or the swivel or becket B directly.

Referring to the swivel or becket B, the same comprises sections 21 and 22, the same respectively including bodies 23 and 24, of elongated formation, which at their upper ends are provided with apertured bearings 25, thru which the bolt 20 may be received in case the becket B is directly supported on the traveling block as illustrated in Figure 7, or which may receive threaded spindles 85 28 at the lower end of the swivel frame C, in case the latter is used. The sections 21 and 22 are supported in a parallel relation and the same at the lower ends are provided with reduced inwardly extending supports 30 and 31, 90 which are complementary; these supports each extending one-half the width of the body 23 and 24 respectively. In height the reduced extensions are less than the height of the bodies of the sections, and above the extensions 30 and 31 is provided a space 36 wherein the link 37 of the single link elevator D may be received, as illustrated in Figure 1 of the drawings. The sections 21 and 22 swing in parallel planes, on the spindles 28, 100

in the relation illustrated in Figure 3 of the drawings, so that the supporting extensions 30 and 31 may be moved away from each other to permit the single link elevator link 37 to be received in the space 36, as is quite apparent from Figure 3 of the drawings.

In order to maintain the sections 21 and 22 in a secured position against liability of accidental opening at any time, a reciprocating latch member 40 is provided, reciprocably carried transversely on the section 22, an end 41 of which is adapted to enter a socket 43, of the other section 21, in order to maintain the sections 21 and 22 against liability of accidentally coming apart. In the section 22 which receives the latch pin 40 is a socket 44 which receives a spiral spring 45 under compression; a detachable cap 46 being provided on the section 22 for maintaining the spring 45 under compression; the spring 45 acting against a pin 48 carried by the latch pin 40, to urge the latch pin end 41 normally into the socket 43, as can readily be understood from Figure 6 of the drawing.

At opposite sides the bodies 23 and 24 are provided with outward extensions 48 and 49 respectively, having sockets 50 therein, with entrance ways 51 reduced in height with respect to the sockets 50; said entrance ways opening outwardly, and the said extensions and sockets being provided for receiving the links 60 and 61 of double link elevator E in the relation illustrated in Figure 4 of the drawings. The swivel supporting ends of the links are of course shorter in length at their upper cross section than the width thereof, so that the said links may be received in the sockets 50 and cannot laterally be moved therefrom thru the reduced entrance ways 51, as can readily be understood by anyone skilled in this art. It is to be particularly noted that in using the single link elevator, the support of the link 37 on the supporting extensions 30 and 31 will all the more tend to maintain the sections 21 and 22 in an assembled relation against liability of accidental detachment.

Referring to the becket B as supported by the swivel frame C; the swivel frame C as illustrated in the drawing comprises a cylindrical ring shaped body 65, having spaced upper extensions 66 and 67 provided with top apertured bearings 68 and 69, adapted to receive the bolt 20 between the side plates 15, as can readily be understood. The ring-shaped body 65 at its juncture with the spaced extensions 66 and 67 is provided with an annular shoulder 70, and below the shoulder 70 is provided a socket 71, which has an annular shoulder 72 at the bottom thereof.

The swivel frame C may also be considered as including a substantially T-shaped swivel bolt or member 75, comprising the vertical shank 76 which extends upwardly into the passageway 78. At its upper end the

vertical portion 76 is provided with a detachable adjusting nut 79, screw threaded thereon, and below the nut 79 is received an anti-friction construction 80, consisting of upper and lower races with ball bearings 70 therebetween; the lower race resting on the shoulder 70 when in elevator supporting position. Between the lower race of the roller bearing anti-friction construction 80 and the shoulder 72 is a spiral compression spring 85, which normally urges the anti-friction bearing 80 away from the shoulder 70, to the position illustrated in Figure 2, and draws the becket B upwardly to the position illustrated in the said figure. However, when a load is supported by the becket or swivel B, the load will pull the anti-friction bearing 80 downwardly upon the shoulder 70, under the weight of the load, and the load will be resiliently supported by the very strong spring 85, to a certain extent, to buff the supporting action and relieving some strains on the construction.

At its lower end the T-shaped swivel bolt 75 includes the body 88, from the ends of which extend the spindles 28, it being understood that the bearings 25 of the becket frame sections are connected at opposite ends of the body 88, as illustrated in the drawing.

From the foregoing description of this invention it is apparent that a novel becket has been provided for supporting elevators, which may be swivelly mounted or directly pivoted to a traveling block, for supporting single or double link elevators in a novel and efficient relation.

Various changes in the shape, size, and arrangement of parts may be made to the form of invention herein shown and described, without departing from the spirit of the invention or the scope of the claims.

I claim:

1. In a traveling block construction a sheave, a sheave frame in which the sheave is mounted, a frame horizontally pivoted directly on said sheave frame, a reciprocating bolt vertically carried by the last mentioned frame below its pivot connection, spring means normally urging said bolt upwardly, and an elevator supporting member carried by said bolt at its lower end.

2. In a traveling block construction a sheave frame, a second frame, a horizontal bolt connecting the second frame to the sheave frame, said second frame having passageways therethrough, a single bolt reciprocably mounted in said passageways for vertical movement, a spring urging the bolt upwardly into the second frame, said bolt having horizontal extensions on the lower end thereof, and an elevator supporting frame movable on said horizontal extensions for horizontal swinging.

3. In an elevator supporting construction a frame comprising a body having a passage

way therethrough, a vertical bolt in said passageway, said body having a lower shoulder in the passageway and an upper shoulder above the lower shoulder, an anti-friction bearing about the upper end of the bolt, means at the upper end of the bolt to prevent the anti-friction bearing from moving away from the bolt, a spiral compression spring around the bolt resting on the lower shoulder and at its upper end against the anti-friction bearing for normally forcing the anti-friction bearing away from the upper shoulder, said bolt at the lower end having laterally extending spindles, a becket comprising a pair of sections pivoted on said spindles, with the sections in spaced relation immediately below the bolt, said sections having spaced inwardly facing extensions at the lower end thereof of a complementary nature for receiving thereon an elevator link or hook.

4. In an elevator supporting construction a frame comprising a body having a passageway therethrough, a vertical bolt in said passageway, said body having a lower shoulder in the passageway and an upper shoulder above the lower shoulder, an anti-friction bearing about the upper end of the bolt, means at the upper end of the bolt to prevent the anti-friction bearing from moving away from the bolt, a spiral compression spring around the bolt resting on the lower shoulder and at its upper end against the anti-friction bearing for normally forcing the anti-friction bearing away from the upper shoulder, said bolt at the lower end having laterally extending spindles, a becket comprising a pair of sections pivoted on said spindles, with the sections in spaced relation immediately below the bolt, said sections having spaced inwardly facing extensions at the lower end thereof of a complementary nature for receiving thereon an elevator link or hook, and latch means for holding said sections together against relative pivotal movement on said spindles.

5. An oil well becket comprising a pair of elongated sections having facing reduced complementary extensions less in height than the length of said sections, and latch means carried by said sections for holding the same in an assembled relation with the extensions held together and the rest of the sections spaced.

6. In an elevator supporting apparatus a becket construction comprising a pair of pivoted sections each including depending elongated bodies with lower laterally extending facing complementary extensions reduced in height and width with respect to said bodies, and a resiliently urged latch pin carried by one of the sections for engaging the other section to hold said extensions in an assembled complementary engaging relation with the rest of the sections spaced for supporting an elevator hook or link.

7. In an elevator supporting apparatus a becket construction comprising a pair of sections each including elongated bodies having at one end thereof laterally extending complementary extensions reduced in height and width with respect to said bodies, and a resiliently urged latch pin carried by one of the sections for engaging the other section to hold said extensions in an assembled complementary relation for supporting an elevator hook or link, said bodies of the extensions having laterally outwardly extending projections provided with link receiving sockets therein.

8. In a becket the combination of a pair of sections each including elongated bodies having at similar ends thereof apertured bearings and at the opposite ends thereof having laterally inwardly extending reduced elevator link supporting complementary extensions, said bodies along the outer sides thereof having projections with outwardly opening link receiving sockets.

9. In a becket the combination of a pair of sections each including elongated bodies having at similar ends thereof apertured bearings and at the opposite ends thereof having laterally inwardly extending reduced elevator link supporting complementary extensions, said bodies along the outer sides thereof having projections with outwardly opening link receiving sockets, and means for holding said sections against relative movement away from each other at the ends upon which said inward extensions are provided.

10. In an oil well becket the combination of a support, a pair of elongated sections pivoted at their upper ends to the support, the sections at their lower ends having facing reducing complementary extensions less in height than the height of said sections, the sections being so pivoted to the support that the extension may swing counter to each other or into engagement with each other to receive a link of an elevator or to permit its detachment with respect thereto, and means at the free movable ends of said sections to hold said sections in assembled relation against relative swinging, with the extensions abutting and the portions of the sections above the extensions relatively spaced.

11. In a becket construction, the combination of a two-piece body, means movably connecting said pieces together, said pieces having complementary facing extensions thereon in a normal overlapping assemblage to provide a support for a single link elevator between said pieces, said pieces at the remote sides from said extensions having spaced supporting extensions for receiving a double link elevator.

JAMES S. TAYLOR.
